(57) **CLAIM**

The ornamental design for a vehicle entertainment system for a headrest, as shown and described.

DESCRIPTION

FIG. 1 is a perspective view of a vehicle entertainment system for a headrest showing my new design.

FIG. 2 is a perspective view of thereof.

FIG. 3 is a top view of thereof.

FIG. 4 is a front view of thereof.

FIG. 5 is a bottom view of thereof.

FIG. 6 is a rear view of thereof.

FIG. 7 is a side view of thereof; and,

FIG. 8 is an opposite view of thereof.

The broken lines in the drawings are for the purpose of showing environmental structure and do not form part of the design to be patented.

1 Claim, 4 Drawing Sheets

FIG. 1

FIG. 2

FIG. 3

FIG. 4

FIG. 5

FIG. 6

FIG. 7

FIG. 8
